UNITED STATES PATENT OFFICE.

LAWRENCE VIVIRITO, OF CHICAGO, ILLINOIS.

DESIGN FOR A LAMP BASE.

Application filed November 23, 1925. Serial No. 15,506. Term of patent 3½ years.

To all whom it may concern:

Be it known that I, LAWRENCE VIVIRITO, a citizen of the United States, residing at Chicago, in the county of Cook and State of Illinois, have invented a new, original, and ornamental Design for a Lamp Base, of which the following specification, reference being had to the accompanying drawing, forms a part thereof.

I claim:

The ornamental design for a lamp base, substantially as shown.

LAWRENCE VIVIRITO.
